HOLDER FOR A WELDER'S BRUSH

Jack Charles Honhart, 98 Manor Ave.,
Birmingham, Mich.

Filed Aug. 12, 1960, Ser. No. 49,258
5 Claims. (Cl. 15—105)

This invention relates to a combined brush holder and chisel particularly adapted for the cleaning of welds.

In the fusing together of metal or alloys by a welding process, electrodes are consumed and they leave on the work a residue of metal and slag. It is desirable in order to present a sound weld that this residue and flux be chipped off and brushed away. To this end I have invented an improved combined brush and chisel holder, related to a similar device as described and claimed in my earlier Letters Patent numbered 2,368,988, issued February 6, 1945, and 2,786,221 issued March 26, 1957.

By my present invention I have improved the tool disclosed in my earlier issued patents in several respects to make it stronger, sturdier and more rigid, resulting in a tool which is more efficient and more useful to the person who uses it than similar tools heretofore used.

Accordingly it is an important object of the present invention is to provide a combination chipping chisel and brush holder affording a strong and rigid support for the brush holding member.

Another object of my invention is to provide an improved brush holding member which is strong and rigid and which, at the same time, affords a substantial receptacle for the brush back by encasing it and maintaining it all around.

A further object resides in the provision of a substantially fully enclosed channeled box surrounding the edges of a brush back to provide a strong brush holding support which can be economically fabricated, and wherein a strong spring yieldingly and firmly holds the brush in assembled relation in the channelled box.

Yet another object of my invention is to provide a strong and rigid support between a handle and a brush holding box to insure the provision of a tool capable of withstanding the repeated impact and shock loads to which the tool is subjected in normal use.

Other objects and advantages of this invention will appear in the following description and appended claims, reference being had to the accompanying drawings forming a part of this specification wherein like reference characters designate corresponding parts throughout the several views.

In the drawings:

FIG. 1 is a side elevational view of one desirable embodiment of my invention.

FIG. 2 is a fragmentary sectional view taken substantially on the line 2—2 of FIG. 1 looking in the direction of the arrows.

FIG. 3 is a fragmentary perspective view taken in the direction of the arrow 3 of FIG. 1, illustrating the reinforced juncture between the side and end walls of the brush holding saddle.

FIG. 4 is a sectional view taken substantially on the line 4—4 of FIG. 1, looking in the direction of the arrows.

FIG. 5 is a fragmentary side elevational view of another desirable embodiment of my invention.

FIG. 6 is a view similar to FIG. 2 taken substantially on the line 6—6 of FIG. 5 looking in the direction of the arrows.

FIG. 7 is a side elevational view of still another desirable embodiment of my invention.

FIG. 8 is a fragmentary sectional view taken substantially on the line 8—8 of FIG. 7 looking in the direction of the arrows.

2

Before explaining the present invention in detail, it is to be understood that the invention is not limited in its application to the details of construction and arrangement of parts illustrated in the accompanying drawings, 5 since the invention is capable of other embodiments and of being practiced or carried out in various ways. Also it is to be understood that the phraseology or terminology employed herein is for the purpose of description and not of limitation.

10 Referring now in more detail to the embodiment of my invention illustrated in FIGS. 1 and 2, the tool is shown to comprise a handle 1, which may be made of wood or of coiled wire or other suitable material and having a rod-like shank 2 which projects into the chisel 3. A 15 brush holding saddle 4 is mounted on shank 2 and includes a box-like sheet metal construction having formed along its bottom a longitudinally extending stiffening rib 5 preferably substantially centrally positioned thereon.

The brush holding saddle 4 has at the outer end a 20 riser 6 having its extremity 7 turned back to overlie and engage and clamp the lower edge of the brush back 8, which for example may be formed of wood, metal, or other suitable material. The inner end of the brush holding saddle 4 carries a spring clip 9 which engages 25 the lower edge of the brush back 8 at its forward end to maintain the brush back in place in the saddle 4. The clip 9 is secured to the saddle 4 by inserting the hooked foot 9' thereof through a hole 4' formed in the saddle; the resilient bias of the clip provides a positive retention 30 force. The spring clip 9 may be pried open by the use of any suitable tool such for example as the shank of a screw driver to relieve the end of the brush so it may be freed from the holder at will, as described and claimed in my prior Letters Patent 2,786,221. In my improved 35 construction as disclosed herein the spring 9 urges the brush back 8 firmly into the saddle 4; however, there is no tendency for the saddle to open up at the outer end because the sides slightly overlap the end and thereby restrain the end from opening, as more clearly shown 40 in FIG. 3.

For the purpose of containing the brush back within the brush holding saddle 4, a pair of upturned wings or flanges 10 and 10' are employed which extend the length of the saddle. This provides a brush holding saddle 45 which is rigid and less subject to damage by rough usage or handling. At the same time it provides a holding saddle which affords a more substantial support for the brush, and which maintains it more securely in place. The holding saddle is also inexpensive to manufacture because it is drawn from a simple sheet metal blank; in some instances it may be deemed expedient for economy of manufacture to employ heavier stock 50 and omit the stiffening rib 5.

The outer end of the brush holding saddle 4 is preferably welded or otherwise rigidly secured to the end of the shank of the chisel 3, a rigid construction being provided by reason of the fact that the end of the shank 2 of the handle is also fixed to the shank of the chisel 3. The juncture between the side walls 10 and 10' with the 55 end wall 6 is built up and reinforced to provide a rigid and strong end structure as shown in FIG. 3. The inner end of the brush holding saddle has a disc-like down-turned guard 11. The rod-like shank 2 is inserted through a hole substantially in the center laterally of the guard, and the guard and the shank are welded together as shown in FIG. 4.

To provide a more rigid and strong structure capable of withstanding the severe shock stresses to which the device is subjected, there is provided a reinforcing bridge 70 construction between the rod-like shank 2 and the brush holding saddle 4 at a portion of the shank intermediate the guard 11 and the chisel 3. To this end I provide the shank

2 with an arcuate bend 12 to bring the shank into contact with the bottom surface of the brush holding saddle. This bent portion 12 of the shank 2 and the bottom of the saddle are welded or otherwise securely fastened to one another as illustrated at 20 to provide a rigid structure. The arcuate bent portion 12 is preferably, but not necessarily, located at a position substantially equidistant to the ends of the brush holding saddle. This provides a more rigid and more substantial support for the brush holding saddle, making a better and more useful tool.

FIGS. 5 and 6 represent another embodiment of the improved tool in which the rod-like shank 2 is substantially straight. The brackets 13 and 13' have their ends 14 and 14' welded or otherwise fastened to the rod-like shank 2, and their other ends are provided with turned out wings 15 and 15' bent substantially at right angles. These wings 15 and 15' are welded or otherwise fastened to the bottom of the brush holding saddle 4.

With reference to the embodiment illustrated in FIGS. 7 and 8, it will be noted that the tool is shown with a supporting block 16 of metal inserted between the substantially straight shank 2 and the bottom of the brush holding saddle 4. This block is welded or otherwise fastened to both the shank and the bottom of the brush holding saddle.

The fastening brackets of FIGS. 5 and 6, and the supporting block of FIGS. 7 and 8, may be inserted at any intermediate position between the outer and inner ends of the brush holding saddle, or they may extend the whole length of the brush holding saddle without departing from the scope and spirit of the present invention.

What I claim is:

1. In a weld cleaning tool having a chisel member and a brush, a handle having a shank secured to the chisel member, a brush holder of formed sheet metal defining an elongated channel adapted to receive the back of a brush and provide substantial support along the length thereof on three sides, means connecting the base of the chisel member and one end of the brush holder, means supporting the opposite end of the brush holder in spaced relation from the handle and shank, said shank of said handle having an arcuate bent portion adapted to lie adjacent the back of the brush holder to support the same, and said bent portion being welded to the back of the brush holder.

2. In a weld cleaning tool having a chisel member and a brush, a handle having a shank secured to the chisel member, a brush holder of formed metal defining an elongated channel adapted to receive the back of a brush and provide substantial support along the length thereof on three sides, means connecting the base of the chisel member and one end of the brush holder, means connecting the opposite end of the brush holder and the handle in spaced relation, and a bracket welded to said shank and to the back of said brush holder between said chisel member and said handle to provide a reinforced connection between said shank and the back of said brush holder.

3. In a weld cleaning tool, a shank, a handle secured to one of said shank, a chisel member secured to the

other end of said shank, a brush-holding saddle consisting of an elongated box-like receptacle having a bottom, said saddle having its one end secured in spaced relation to said shank near said handle and its other end secured to the base of said chisel member, said saddle being provided at its outer end with a riser having a step-like wing turned back to overlie the back of a brush positioned therein to retain the brush in said saddle, a spring wire clip on the other end of said saddle to normally bear down on the back of a brush positioned within said saddle, said saddle having turned-up sides integral with said bottom and extending the length thereof and joined to said riser to securely contain the back of a brush, an arcuate bend in said shank adapted to contact said bottom of said saddle, and means connecting said bottom of said saddle to said arcuate bend at the point of contact whereby the intermediate portion of said saddle is provided with substantial support.

4. In a weld cleaning tool, a shank, a handle secured to one end of said shank, a chisel member secured to the other end of said shank, a brush-holding saddle consisting of an elongated box-like receptacle having a bottom, said saddle having its one end secured in spaced relation to said shank near said handle and its other end secured to the base of said chisel member, said saddle being provided at its outer end with a riser having a step-like wing turned back to overlie the back of a brush positioned therein to retain the brush in said saddle, a spring wire clip on the other end of said saddle to normally bear down on the back of a brush positioned within said saddle, said saddle having turned-up sides integral with said bottom and extending the length thereof and overlapping said riser to securely contain the back of a brush, and a support bracket secured between said shank and said bottom of said saddle intermediate the ends of said shank.

5. In a weld cleaning tool, a shank, a handle secured to one end of said shank, a chisel member secured to the other end of said shank, a brush-holding saddle consisting of an elongated box-like receptacle having a bottom, said saddle having its one end secured in spaced relation to said shank near said handle and its other end secured to the base of said chisel member, said saddle being provided at its outer end with a riser having a step-like wing turned back to overlie the back of a brush positioned therein to retain the brush in said saddle, a spring wire clip on the other end of said saddle to normally bear down on the back of a brush positioned within said saddle, said saddle having turned-up sides integral with said bottom and extending the length thereof and overlapping said riser to securely contain the back of a brush, and a support block secured between said shank and said bottom of said saddle intermediate the ends of said shank.
